UNITED STATES PATENT OFFICE.

EDWIN C. RENAUD, OF ST. JOSEPH, MISSOURI.

COMBINED TELEPHONE DIAL AND ADVERTISEMENT ILLUMINATOR.

Application filed September 8, 1925. Serial No. 55,159.

- My invention relates to improvements in electrical devices for the illumination of the dials of dial operated telephones and the simultaneous display of advertising matter.
- 5 The object of my invention is to provide a novel support for a telephone, said support having means for automatically illuminating the dial of a dial operated telephone and simultaneously illuminating advertisements, 10 when the receiver is removed from the hook of the telephone.
- A further object of my invention is to provide a device of the kind described which is simple in construction, cheap to make, 15 effective in its action, durable and not liable to get out of order, and which is easily and readily adaptable for use with dial telephones now in use, and the mechanism of which is independent of the telephone mechanism, other than serving as a support for the telephone and being operative by the lessening of the weight supported when the receiver is removed for use.

The novel features of my invention are 25 hereinafter fully described and claimed.

In the accompanying drawings, which illustrate the preferred embodiment of my invention,

Fig. 1 is a perspective of my improved 30 illuminator, shown with a dial telephone resting thereon.

Fig. 2 is a vertical sectional view thereof, the telephone being absent.

Fig. 3 is a plan view of the device partly 35 broken away.

Fig. 4 is a diagrammatic view of the electric circuit.

Similar reference characters designate similar parts in the different views.

40 1 designates the base, on which is fastened a hinge 2, the upper extremity of said hinge being attached to the inside of an inverted pan shaped body 3 of the device, the said body having an annular downwardly extending side wall containing openings 4 for the reception of a transparent strip 7 containing advertisements, said body having a flat top 5 for the support of a dial telephone 6, said top being provided with 45 an upwardly extending tubular member 8 having a hood 10 containing an electric light bulb 9.

The said electric light bulb 9 has its terminals respectively connected to conductors 50 11 and 12, which respectively connect with

the terminals of a current source, such as a battery 13.

An electric light bulb 16, placed upon the base 1, within the interior of the hollow movable body of the device, is included in 60 the conductor 11 and is adapted to illuminate the advertising matter placed on the transparent strip 7 which covers the openings 4 in the side of the hollow movably hinged body 3, a simultaneous lighting of 65 the said electric light bulbs 9 and 16 being accomplished through the closing of the circuit due to the upward movement of a contact member 14 of a circuit closer in said circuit, said member 14 being attached to 70 the under surface of the top 5, and, on the upward movement of said top, having contact with the other circuit closer member 15 mounted on the base 1, said contact members 14 and 15 being included in the conductor 12.

The upward movement of the hollow movably hinged body 3 of the device occurs when the weight of the telephone resting on the top thereof, is lessened by the removal of the receiver 21 from the hook 22 provided therefor on the telephone, this lessening of weight permitting a spring 17, which rests at its lower end on the base 1 and which encircles a vertical post 18 80 mounted on the base 1, to press upwardly upon a flange 19 at the lower end of a hollow member 20 which is attached at its upper extremity to the under surface of the top 5 of the movable hollow body 3. Such upward movement causing the hollow movable body 3 to move to the position illustrated by dotted lines in Fig. 2. The lower end of the hollow member 20 encircles the upper end of the vertical rod 18 thus preventing 85 undue lateral motion or wobbling of the member 20.

The closing of the electric circuit through the electric lamp bulbs 9 and 16 by means of contact of the horizontal portions of the 100 circuit closer members 14 and 15, in the manner previously described, causes the lighted bulb 9 to illuminate the dial 24 of the dial operated telephone 6, when the latter is properly disposed on the top 5, and also, 105 by means of the lighted bulb 16, simultaneously furnishes illumination of the advertisements on the transparent strip 7 covering the openings 4.

When the receiver 21 is replaced on the 110

hook 22, its weight will cause the body 3 to swing downwardly to the position shown in solid lines in Fig. 2, thereby separating the circuit closer members 14 and 15 and 5 opening the circuit which includes the bulbs 9 and 16.

I do not limit my invention to the structure shown and described, as various modifications, within the scope of the appended 10 claims, may be made without departing from the spirit of my invention.

What I claim is:

1. In an illuminator of the kind described, a base, a hollow body vertically movable 15 on said base and having a side wall provided with openings adapted to be covered by transparent material containing advertising or similar matter, said body having a flat top adapted to support an article, such as 20 a dial telephone, means for forcing said body upwardly when the weight carried thereby is reduced a predetermined amount, an electric circuit including a circuit closer arranged to close when said body moves upwardly and to open when said body moves 25 downwardly, a current source in said circuit, and two electric light bulbs in said circuit, one bulb being disposed so as to illuminate said article, and the other disposed in said body and adapted to project rays through said openings.

2. In an illuminator of the kind described, a base, a hollow body vertically movable on said base and having openings adapted 35 to be covered with transparent material containing advertising or similar matter, said body having a flat top adapted to support an article, such as a telephone, a spring connecting said base and said body and adapted 40 to force said body upwardly when the weight carried thereon is reduced a predetermined amount, an electric circuit including a circuit closer actuated by said body to respectively close and open said circuit when said 45 body moves upwardly and downwardly, a current source in said circuit, and two electric light bulbs in said circuit, one being located above said flat top so as to illuminate said article, the other bulb being in said 50 body and disposed so as to project rays through said openings.

3. In an illuminator of the kind described, a base, a hollow body vertically movable on said base, and having openings adapted 55 to be covered by transparent material containing advertising or similar matter thereon, said body being adapted to support a dial telephone thereon, means, inactive, when said body is depressed, for forcing 60 said body upwardly when a predetermined weight is removed from said body, and electric light illuminating means controlled by said body for simultaneously illuminating the dial of said telephone and for projecting 65 light through said openings and arranged

to effect such illumination upon the upward movement of said body and to discontinue the illumination when said body moves downwardly.

4. In an illuminator of the kind described, 70 a base, a hollow body vertically movable on said base and adapted to support an article, such as a telephone, and having side openings and having an upwardly extending tubular member having a hood, a vertical post secured to said base, a coil spring 75 encircling said post and resting on said base and bearing against said body and adapted to force said body upwardly, said body being adapted to be depressed by said article 80 and adapted to be lifted by said spring when the weight on said body is lessened a predetermined amount, two electric light bulbs, one located in said body and adapted to project light through said openings, the other bulb being disposed in said hood and adapted to project light on said article, an electric circuit including said bulbs, and a circuit closer in said circuit comprising two contact members, one attached to said body 85 and the other to said base, and arranged to contact with each other when said body is upwardly moved by said spring and to separate when said body lowers, and a current source in said circuit. 90

5. In an illuminator of the kind described, a base, a hollow body vertically movable thereon having a side wall provided with openings, said body being adapted to support a dial telephone, transparent material across said openings containing advertising or similar material, a spring for moving said body upwardly when said telephone or a sufficient portion thereof is removed from said body, and an electric circuit including 100 a circuit closer arranged to close when said body rises and to open when said body lowers, a current source in said circuit and lighting means in said circuit arranged when said circuit is closed to project light through said openings and said transparent material and to simultaneously project light upon the dial of a telephone, when the latter is properly disposed on said hollow body. 110

6. In an illuminator of the kind described, a hollow body having openings adapted to be covered by transparent material containing advertising or similar matter, said body being adapted to support a dial telephone, an electric circuit including a current source, lighting means in said circuit for simultaneously projecting light through said openings and upon said dial, and circuit controlling means arranged to open said circuit when said telephone is on said body and to close said circuit when said telephone on a predetermined portion thereof is removed from said body. 120

7. In an illuminator of the kind described, the combination with a dial telephone hav- 125

- ing a receiver, of a base, a member adapted to support said telephone vertically movable on said base, means, depressible by the weight of said telephone and its receiver, 5 for forcing said member upwardly when the telephone or its receiver is removed from said member, and means controlled by said member for illuminating the dial of said telephone when said member moves upward- 10 ly and rendered inactive when said member is depressed.
8. In an illuminator of the kind described, the combination with a dial telephone having a receiver, of a base, a member adapted to 15 support said telephone vertically movable on said base, means for forcing said member upwardly when the weight of said telephone or its receiver is removed from said member, the weight of said telephone and its receiver normally forcing said member downwardly, and an electric circuit including means for illuminating the dial of said telephone, and including a circuit closer operative to close said circuit by said member 20 25 when the latter moves upwardly and to open said circuit when said member moves downwardly.
9. In an illuminator of the kind described, a base, a member vertically movable thereon 30 adapted to support a dial telephone and its receiver, means for forcing said member upwardly, active for the purpose when said telephone or its receiver has its weight removed from said member and inactive there- 35 for when said telephone and its receiver are supported by said member, and an electric circuit including an electric lighting bulb disposed so as to project light upon the dial of said telephone when the latter is sup- 40 ported in operative position on said mem-
- ber and said circuit is closed, said circuit including a circuit closer operative by said member on its upward movement to close said circuit and operative by said member on the downward movement of the latter to open said circuit.
10. In an illuminator of the kind described, a base, a member vertically movable thereon adapted to support a dial telephone and its receiver, means for forcing said member upwardly, operative when the weight of said telephone or its receiver is removed from said member, and an electric circuit including an electric lighting bulb disposed so as to illuminate the dial of said telephone when 55 said circuit is closed and the telephone is in operative position on said member, said circuit including two contact members respectively attached to said base and to said member and arranged to contact with each other 60 to close said circuit when said member moves upwardly and to separate when said member moves downwardly, the weight of said telephone and its receiver serving to depress said member. 65
11. In an illuminator of the kind described, the combination with a telephone having a hook and a receiver mounted on the hook and a dial carried by said telephone, of a support for said telephone, and means actuated by said support for illuminating said dial and operative independently of said hook when the telephone is removed from said support or the receiver is removed from said hook, and inactive for the purpose when 70 the telephone is on said support and the receiver is resting on said hook. 75

In testimony whereof I have signed my name to this specification.

EDWIN C. RENAUD.
